Attorney, Agent, or Firm—Dowell & Dowell[57] **CLAIM**The ornamental design for an inflator bulb for a sports
glove, as shown and described.**DESCRIPTION**FIG. 1 is a top plan view of an inflator bulb according
to our design, the dashed lines representing a sports
glove to which the inflator bulb is applied and forming
no part of the present invention;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a view similar to FIG. 1 illustrating a second
embodiment of an inflator bulb for a sports glove ac-
cording to our invention;

FIG. 8 is a front elevational view thereof;

FIG. 9 is a rear elevational view thereof;

FIG. 10 is a left side elevational view thereof;

FIG. 11 is a right side elevational view thereof;

FIG. 12 is a bottom plan view thereof;

FIG. 13 is a view similar to FIG. 1 illustrating a third
embodiment of an inflator bulb for sports glove accord-
ing to our invention;

FIG. 4 is a front elevational view thereof;

FIG. 15 is a rear elevational view thereof;

FIG. 16 is a left side elevational view thereof;

FIG. 17 is a right side elevational view thereof; and,

FIG. 18 is a bottom plan view thereof.

The dashed lines illustrated in the drawing represent the
environment in which the inflator bulb is situate and
form no part of the present invention.FIG.1
